US0D1100931S

(12) **United States Design Patent** (10) Patent No.: **US D1,100,931 S**
(45) Date of Patent: ** Nov. 4, 2025

(54) **COMPUTER WITH GRAPHICAL USER INTERFACE**

(71) Applicant: **GOOGLE LLC**, Mountain View, CA (US)

(72) Inventors: **Steve Tompkins**, Mountain View, CA (US); **Isaac VanDuyne**, Mountain View, CA (US)

(73) Assignee: **Google LLC**, Mountain View, CA (US)

(**) Term: **15 Years**

(21) Appl. No.: **29/928,125**

(22) Filed: **Feb. 8, 2024**

Related U.S. Application Data

(60) Continuation of application No. 29/838,202, filed on May 11, 2022, now Pat. No. Des. 1,030,785, which is a continuation of application No. 29/680,453, filed on Feb. 15, 2019, now Pat. No. Des. 955,414, which is a division of application No. 29/584,017, filed on Nov. 10, 2016, now Pat. No. Des. 844,644.

(57) **CLAIM**

The ornamental design for a computer with graphical user interface, as shown and described.

DESCRIPTION

The FIGURE is a front view of a computer with graphical user interface, according to our design.

The two outermost broken lines and the broken line oval depict a computer. The remaining broken lines depict a display screen and portions of the graphical user interface. All broken lines form no part of the claimed design.

1 Claim, 1 Drawing Sheet
